UNITED STATES PATENT OFFICE.

EDWARD W. SELKIRK, OF CHICAGO, ILLINOIS.

WINDOW-SASH.

No. 887,968.

Specification of Letters Patent.

Patented May 19, 1908.

Application filed October 23, 1907. Serial No. 398,821.

To all whom it may concern:

Be it known that I, EDWARD W. SELKIRK, a citizen of the United States, and resident of the city of Chicago, county of Cook, and 5 State of Illinois, have invented certain new and useful Improvements in Window-Sashes, of which the following is a specification, and which are illustrated in the accompanying drawings, forming a part thereof.

10 The invention relates particularly to means for lubricating runways of window sashes and while being applicable to windows in any situation is of more especial value in connection with windows of railway cars.

15 The invention consists in the structure hereinafter described and which is illustrated in the accompanying drawings, in which

Figure 1 is a detail elevation of a window sash and casing some portions being broken away to show the internal construction; Fig. 2 is a detail on the line 2—2 of Fig. 1; Fig. 3 is a detail section on the line 3—3, of Fig. 1; Figs. 4 and 5 are perspective views of elements of the lubricating block; and 25 Fig. 6 is a perspective of a clamp to secure the lubricating elements together.

A part of the frame of a window sash is represented at 10, a part of a window casing at 11, the usual strips applied to the window 30 casing to form the runway for the sash are shown at 12, 13. A recess is formed in the edge-face of the sash, as shown at 14, this recess extending entirely across the sash and being of a depth not exceeding the thickness 35 of the strips 12, 13. The side walls 15, 16 of this recess are parallel. Within the recess 14 there is seated a block 17 of solid lubricant, such as graphite or soapstone and back 40 of this block, housed within the recess 18 in the window sash there is located a spring 19, shown as being of wire wound in helical form for forcing the block outwardly and causing it to bear against the face of the casing 11. The block 17 is sectional being com-

45 posed of three elements 20, 21, 22 oblong rectangular in shape and lying side by side. The two outer elements 20 and 22 are identical in form and only one of them is therefore illustrated in detail. The central element 21 is transversely recessed across its inner face as shown at 23 and within the recess is located an expansion spring 24, also shown as being in helical form, this spring bearing against the inner faces of the elements 20 and 22 and forcing them apart so

as to cause them to bear against the side edges of the strips 12, 13.

A bearing plate 25 preferably of metal is interposed between the block 17 and the spring 19, covering the recess 23 and overlapping the outer elements 20, 22 so that the entire block is urged outwardly by the spring. Preferably this bearing plate 25 is provided with inturned flanges at two of its edges, as shown at 26, 27 which enter their suitable 60 registering grooves 28, 29 and 30, 31 cut across the inner face of the several elements of the block, thereby maintaining the plate in its proper position while allowing the free movement of the side elements under the influence of the spring 24.

The lubricating block having been placed in its pocket and the sash properly hung the ways within which the sash run will be continuously lubricated, thereby preventing the 75 annoying sticking of the sash. Any suitable solid lubricant may be used, preferably the material being such that it will not rapidly wear away and will not be greasy, in order that it may not cause an accumulation of 80 dirt.

I claim as my invention—

1. In combination, a window sash having a recess in its side edge and a spring projected lubricating body seated within the recess. 85

2. In combination, a window sash having a recess in its side edge, a sectional block of lubricating material seated within the recess, means for expanding the block laterally and means for urging the block outwardly. 90

3. In combination, a window sash having a recess in its side edge, a lubricating block comprising inner and outer sections, the inner section being transversely recessed, an expansion spring seated within the recess of 95 the inner section and bearing against the outer sections, and an expansion spring back of the block and urging it outwardly.

4. In combination, a window sash having a recess in its side edge, a sectional block of 100 lubricating material located within the recess, a bearing plate back of the block and overlapping its several sections and an expansion spring reacting between the bearing plate and the bottom of the sash recess. 105

5. In combination, a window sash having a recess in its side edge, a sectional block of lubricating material located within the recess, a bearing plate back of the block and overlapping its several sections and an ex- 110

expansion spring reacting between the bearing plate and the bottom of the sash recess, the several sections of the block being transversely grooved, the plate having flanges fitting within said grooves.

5. 6. In combination, a window sash having a recess in its side edge, a lubricating block set within said sash recess and comprising an inner and a pair of outer sections, the inner 10 section being transversely recessed, an expansion spring located within the recess of the inner section and bearing against the outer section, a bearing plate at the back of the block to cover the recess of its central section, and overlapping its outer sections, 15 and a spring located between the bearing plate and the bottom of the sash recess.

7. In combination, a window sash having

a recess in its side edge, a lubricating block set within said sash recess and comprising an inner and a pair of outer sections, the inner section being transversely recessed, an expansion spring located within the recess of the inner section and bearing against the outer sections, a bearing plate at the back of the block to cover the recess of its central section, and overlapping its outer sections, and a spring located between the bearing plate and the bottom of the sash recess, the several sections of the block being transversely 25 grooved and a wear plate having flanges fitting within said grooves.

EDWARD W. SELKIRK.
